PORATION OF OHIO

BLANK CARTRIDGE

Application filed March 1, 1930. Serial No. 432,463.

This invention relates to a blank cartridge for use in talking moving pictures. Before the inception of sound pictures blank cartridges had been used in moving pictures. These blank cartridges were constructed solely for the purpose of producing a volume of smoke and flame such that it was readily photographed. In the talking moving pictures the sound recording equipment is adjusted so that it will reproduce sound of the average quality and intensity of the human voice. To do this the recording apparatus is necessarily adjusted to receive sound waves of only moderate intensity. The sound wave resulting from the firing of a rifle, pistol or shotgun consists of a rather sharply defined pressure wave of considerable amplitude and short duration immediately followed by a comparatively long low pressure wave.

It was discovered that blank cartridges previously used, developed a sound wave so intense that it ruptured the delicate filament of the apparatus used to record the sound picture. An urgent need was therefore created for a blank cartridge that would not only provide the necessary smoke and flash for photographic purposes but would also produce a sound wave of the characteristic quality of a shot but at such a reduced amplitude that it would not damage the delicate recording apparatus.

It is the lower harmonics, for instance below 1000 cycles per second which determine the carrying power of the voice, while it is the frequencies above 1000 cycles which determine the articulation or quality. Thus, in producing a blank cartridge suitable for the talking moving pictures we desire to maintain the same band of frequencies at reduced amplitudes, otherwise the sound would be immediately perceived as false, or not possessing the characteristics associated with gun fire. We have invented such a blank cartridge and have attained the desired quality at only one-third the intensity of the former blank. Our new blank cartridges have the characteristic sharp rise in pressure but of lesser amplitude than the regular cartridge. They have the same general harmonics which determine quality but

they also are of smaller amplitude than formerly.

Other objects and certain advantages will be more fully apparent from the description of the accompanying drawings in which:

Figure 1 is a vertical longitudinal sectional view of the cartridge when stood upon its base.

Figure 2 is a view of the primer end of the cartridge.

These new blank cartridges are adaptable for various arms of different calibers. It is this valuable characteristic which has led to the designation, "5-in-1" blank. In the moving pictures it is not necessary to use arms of good shooting qualities since blanks alone and not ball cartridges are used. Therefore, various second-hand arms may be used by the moving picture actors. A cartridge which will operate equally well in several different arms is therefore of much greater value. Our improved blank cartridge is of such a construction that it will operate in .38-40, .44-40 and .45 caliber revolvers and in both .38-40 and .44-40 rifles, and will produce in all these arms the required amount of flash and smoke and the required quality of report or sound. This characteristic is attained by making an outer shell or cartridge of very rigid construction and by reducing or forming the mouth of the shell to conform to the shape of a loaded ball cartridge, and by providing a space or chamber between the outer shell and an inner shell carrying the charge. More specifically, an outer shell or case 1 is formed or reduced to a shape simulating the bullet of a loaded ball cartridge of any suitable caliber such as .38. An inner shell 2 consists of a case smaller in caliber than the outer case, rolled and crimped and containing a powder charge 3 and a confining wad 4 with a primer 5. Between the outer and inner case there is a space or chamber. The bases of the two cases or shells are flush so that the primer carried by the inner shell is properly disposed for use in small arms or ordnance into which the outer case fits. From the point of view of the structure, the outer case

constitutes an adapter suiting small shells

for large caliber arms. From the point of view of sound effects, the outer case provides an explosion chamber larger than the charge.

Both outer and inner case may be made of any suitable material such as metal or non-metal or a combination of metal or non-metal. For instance, the outer case may be made of brass while the inner case may be made partly of brass and partly of paper. Instead of brass any other suitable metal may be used. The construction of the inner case of our blank cartridge provides a substantial reinforcing of the sound due to its configuration, wad and crimp which confine the explosion until pressure have increased to a degree such that the proper quality of sound will be produced. The space between the inner and outer case is so proportioned that a sound wave having the desired characteristics as to quality and intensity is obtained.

The blank cartridges of this invention have the following advantages, features and characteristics:

- 25 1. The visual photographic effect is correct.
2. The size of the cartridge adapts it to fit into the small arms conventionally used.
3. The frequency of vibration and the harmonics are suitable to create the illusion of a normal shot when recorded by apparatus adjusted to record the human voice.
4. The amplitude or pressure of the vibrations is sufficiently low to permit the recording without injury to the apparatus.

By using these blank cartridges the sound of gun fire may be reproduced in a natural manner and yet be recorded without damage to the sound receiving apparatus.

40 Having described our invention, we claim:
1. A blank cartridge for use in talking moving pictures, comprising, an outer case adapted to fit in the arms to be used, an inner shell disposed in and spaced from the outer case, a primer carried by said inner shell and appropriately located for use in said arms, a charge in said inner shell, and means for constricting said charge in said inner shell to produce sound waves of similar frequencies but lesser amplitude than the sound waves produced by normal gun fire.

2. A blank cartridge for use in talking moving pictures, said blank cartridge, comprising, a relatively strong outer case adapted to be inserted in the desired arms, a more fragile shell mounted in but spaced from said case, a charge and primer carried by said second shell, and means for constricting said charge to the degrees necessary to produce sound vibrations of frequencies approximating those produced by normal gun fire.

3. A blank cartridge for use in talking moving pictures, said blank cartridge, comprising, a shell carrying a primer, a charge and a wad, an outer case surrounding said

shell and spaced therefrom, said outer casing adapting said inner shell dimensionally to fit in the desired arms, said spacing providing a chamber adapted to develop sound waves of characteristics similar to those produced by normal gun fire.

4. A blank cartridge for use in talking moving pictures, comprising, an inner shell carrying a charge and a wad, a crimp about the mouth of the shell adapted to constrict the wad, and an outer case having its rear end flush with the rear end of the shell but of greater diameter than the shell thereby adapting the shell to be used in arms of caliber larger than it and providing a chamber about the shell suitable for development of appropriate acoustic properties.

5. A blank cartridge for use in talking moving pictures, comprising, an outer case having the shape of a loaded ball cartridge, and an inner shell of smaller size carrying a charge, wad and primer, the base of the inner shell mounted flush with the base of the outer case.

In witness whereof, we hereunto subscribe our names.

CHARLES L. HOLDEN.
PHILIP P. QUAYLE.
